[57] **CLAIM**

The ornamental design for a housing for a stereo unit, as shown and described.

DESCRIPTION

FIG. 1 is a top, front and left side perspective view of a housing for a stereo unit showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top, front and left side perspective view of a second embodiment of the housing illustrated in FIG. 1;

FIG. 8 is a front elevational view thereof;

FIG. 9 is a top plan view thereof;

FIG. 10 is a bottom plan view thereof;

FIG. 11 is a left side elevational view thereof; and,

FIG. 12 is a right side elevational view thereof.

The rear of the housing of both embodiments is plane and unornamented.
